UNITED STATES PATENT OFFICE.

WILLIAM E. COLE, OF NORFOLK, VIRGINIA.

SHAKING-GRAVE.

No. 900,057.

Specification of Letters Patent.

Patented Sept. 29, 1908.

Application filed April 6, 1906, Serial No. 310,357. Renewed April 24, 1908. Serial No. 429,056.

To all whom it may concern:

Be it known that I, WILLIAM E. COLE, a citizen of the United States, residing at Norfolk, in the county of Norfolk and State of Virginia, have invented certain new and useful Improvements in Shaking-Grates; and I do hereby declare the following to be a full, clear, and exact description of the invention, such as will enable others skilled in the art to which it appertains to make and use the same.

This invention relates to shaking grates for stoves, furnaces and the like, and has for its object to provide a device of the class embodying new and improved features of convenience, economy, reliability and efficiency.

A further object of the invention is to provide ball bearings of improved form for supporting the longitudinally reciprocating grate bars.

With these and other objects in view, the invention comprises certain novel constructions, combinations and arrangements of parts, as will be hereinafter fully described and claimed.

Figure 1 is a longitudinal sectional view through a furnace provided with my improved grate. Fig. 2 is a cross sectional view on line 3—3 of Fig. 1. Figs. 3, 4, and 5 are detail views illustrating the roller supports for the grate-bars.

In its preferred embodiment, the improved shaking grate forming the subject-matter of this application, comprises a frame wall or fire pot 10, preferably rectangular in form and provided at opposite ends with transversely disposed spaced bearing bars 11 rigidly secured thereto adjacent to or in contact with the end walls of the said frame or fire pot. Interposed between the spaced bearing bars 11 are supporting uprights 12, defining spaces for the accommodation of the ends of the reciprocating grate bars and forming, at their upper ends, means for supporting the end portions of the furnace, as the perforate plate 13 or the ledge 14.

Between the spaced bearing bars 11 and intermediate the supporting uprights 12 are secured carriers 15 upon and between which are disposed balls 16. The inner spaced bearing bars 11 are provided with notches or apertures 17 proportioned to accommodate the web 18 of the grate bars, which said web is provided at its opposite ends with grooves 19, proportioned and positioned to rest upon the balls 16. Upon and rigidly secured to or

integral with the web 18 is the grate bar 20 formed with laterally and oppositely extending teeth 21 proportioned to extend adjacent to the teeth 21 of the next adjacent grate bar 60 upon each side. Upon the opposite longitudinal sides of the fire pot are rigidly secured grate pieces 22, having teeth 23 upon their inner sides corresponding in form and proportion to the teeth 21 of the grate bars, 65 and extending laterally inward adjacent to the teeth 21 upon the outer sides of the outer bars.

Beneath the grate bars are mounted rock shafts 24 and 25 in any approved manner as 70 by their respective trunnions 26 and 27, being journaled in bearings 28 and 29, formed in the side walls of the ash pan or pit. The rock shafts 24 and 25 are respectively provided with upstanding lugs 30 and 31 75 spaced on the said shafts in position to engage intervals 32 and 33 defined between downwardly extending lugs 34 34' and 35 35' upon alternate grate bars, so that the lugs of the rock shaft 24 are in operative engagement with alternate grate bars, while the lugs of rock shaft 25 are in similar engagement with the grate bars intermediate.

Upon the lower side of the rock shafts 24 and 25 are respectively formed arms 36 and 85 37, extending downwardly into the ash pit and pivotally connected respectively with links 38 and 39, extending outwardly through the end of the walls 10 of the ash pit. Upon the outer surface of the ash pit wall is pivoted a lever 40 of any approved and convenient form and in any convenient manner as 90 between the ears 41, the said lever being provided with a normally, vertically disposed cross head 42, to the extremities of which are 95 pivotally secured the links 38 and 39.

It will be understood that the device here shown and described may be applied to any ordinary and usual form of stove and furnace, engine, locomotive and the like, and 100 that the grate bars 20 may be plain upon their upper surfaces, as shown, or curved in any desired and approved manner. It will also be understood that the lever 40 may be of any desired and approved length and 105 either straight or curved to be positioned for convenient operation by the operator in charge.

In operation, the oscillation of the lever 40 will oscillate the cross head 42 and reciprocate the links 38 and 39. The links 38 and 110 39 being secured, as shown, to the opposite

ends of the cross head 42, will be given a reciprocatory movement in opposite directions. The links 38 and 39 being pivotally secured to the arms 36 and 37, which are rigidly connected with the rock shafts 24 and 25 will be simultaneously actuated in opposite directions, and the rock shafts consequently rotatably moved in opposite directions. The rotary movement of the rock shafts 24 and 25 in opposite directions will move the lugs 30 and 31 upon their respective shafts simultaneously in opposite directions, and as the said lugs 30 engage grate bars which are in alternation with those engaged by the lug 31, it is obvious that the said grate bars will be simultaneously and alternately moved in opposite directions.

The face of the grate 20 is of the usual tooth type as indicated by 21. The projections 21' on each side of the bar at the end do not support fuel. The plate 13 supports the fuel. The projections 21' are spaced between the uprights 12 so as to guide and hold the grate bar in a vertical position as it moves back and forth longitudinally. The notches 17 in the bearing bar 11 engages and guides the web of the grate and holds it on top of the ball.

It will be noted that at the stoking end of 30 the furnace the perforate plate 13 is provided as a fuel surface and to keep the fire off the ends of the movable grate-bars also, the perforations therein being of such size that any material, which passes through the 35 said plate, is small enough to pass through, between and among the carrying guides, supporting uprights and bearing balls.

The form of furnace herein shown is largely conventional, as it is obvious that the principle involved in moving the alternate grate bars in opposite directions may be satisfac-

torily applied to furnaces of various forms and grate bars of any approved structure.

While the manner of moving the alternate grate bars in opposite directions by means of 45 rock shafts provided with staggered engaging lugs is found to be a convenient, and is a preferred form, it is obvious that the alternate grate bars may be operated in any approved manner, and its application is not 50 limited to the specific form of actuating means.

What I claim is:—

1. In combination with a shaking-grate, two bearing bars, each comprising spaced 55 bars, a series of spaced uprights between said bars, a perforated plate supported by said uprights, a series of ball tracks located between said uprights and balls located thereon, grate-bars provided with fuel supporting 60 surfaces and depending webs resting on said balls, and means for moving alternate grate bars longitudinally in opposite directions.

2. In a shaking grate, two bearing bars each comprising spaced bars, a series of 65 spaced uprights located between said bars, the inner one of said bars being provided with notches located between the uprights, ball tracks below said notches connecting the bars, a ball located thereon, grate bars provided with fuel supporting surfaces and depending webs, said webs passing through the notches of the inner bars and resting on the 70 balls, means for supporting the bearing bars, and means for moving alternate grate bars 75 longitudinally in opposite directions.

In testimony whereof I affix my signature in presence of two witnesses.

WILLIAM E. COLE.
